DESIGN FOR A DRAWING IMPLEMENT

Robert S. Grant, Providence, R. I.

Application March 27, 1934, Serial No. 51,201

Term of patent 7 years

To all whom it may concern:

Be it known that I, ROBERT S. GRANT, a citizen of the United States, residing at 15 Enfield Avenue, in the city of Providence, county of Providence and State of Rhode Island, have invented a new, original, and ornamental Design for a Drawing Implement, of which the following is a specification, reference being had to the accompanying drawing, forming a part thereof, in which:

Fig. 1 is a front view of the implement showing my new design; and

Fig. 2 is an edge view of the same.

I claim:—

The ornamental design for a drawing implement, substantially as shown.

ROBERT S. GRANT.
